UNITED STATES PATENT OFFICE

CHARLES H. JOHNSEN, OF HARVEY, ILLINOIS.

EXTENSION-TABLE.

No. 907,503.

Specification of Letters Patent. Patented Dec. 22, 1908.

Application filed December 28, 1907. Serial No. 408,400.

To all whom it may concern:

Be it known that I, CHARLES H. JOHNSEN, a citizen of the United States, residing at Harvey, county of Cook, and State of Illinois, have invented certain new and useful Improvements in Extension-Tables, of which the following is a specification.

My invention relates to extension tables and the object of my invention is to provide 10 an extension table which may be easily operated to extend the end or main portions of the table and which will automatically place a plurality of leaves in position successively and which may be as readily contracted, the 15 leaves being automatically and successively retracted beneath the table top. Other objects will appear hereinafter.

My invention consists generally in a table comprising the two end portions adapted to 20 be moved toward or from each other in combination with a pair of levers pivotally connected beneath one of the end portions, a plurality of leaves arranged one above the other and supported upon the free ends of said levers when the table is in closed position, means for intermittently raising said levers as the table is extended to raise the leaves 25 successively into position level with the table top and means for locking the leaves in position.

My invention further consists in a table comprising the two end portions in combination with means for moving said portions toward or from each other, a pair of levers pivotally mounted beneath one of said end portions, a plurality of leaves arranged one above the other and supported upon the free ends of said levers when the table is in closed position, means for intermittently raising 30 said levers as the table is extended to raise the leaves successively in position level with the table top, means for locking the first leaf to the edge of the opposite end portion as it is raised into position and means for locking the successive leaves in a like manner to the preceding leaf, and means adapted to pass beneath the leaves to support the same as the ends of the levers are withdrawn from beneath them.

50 My invention further consists in certain

means for preventing endwise movement of the leaves in order that the coacting locking members may properly register and to bring the edges of the leaves into alinement with each other and with the end members of the 55 table.

My invention further consists in various details of construction and arrangements of parts all as will be hereinafter fully described and particularly pointed out in the claims. 60

My invention will be more readily understood by reference to the accompanying drawings forming a part of this specification and in which,

Figure 1 is a bottom plan view of a table 65 embodying my invention in its preferred form, Fig. 2 is a side elevation of the table with the depending molding broken away to illustrate the mechanism, Fig. 3 is a vertical section on the line $x-x$ of Fig. 1, Fig. 4 is a 70 vertical cross section on the line $y-y$ of Fig. 1, Fig. 5 is a side elevation of the table in closed position, Fig. 6 is a detail of the device for extending and retracting the ends of the table, Figs. 7 and 8 are plan and edge 75 views respectively of one of the leaves, Fig. 9 is a detail bottom plan view of a portion of the leaves and the adjacent end members illustrating the locking members, Fig. 10 is a section on the line $z-z$ of Fig. 9, Figs. 11 and 80 12 are details of the leaf raising mechanism, and Fig. 13 is a detail longitudinal section illustrating the leaf supporting device.

Referring to the drawings 1 and 2 indicate the ends or the main portions of the table 85 top and 3-3 and 4-4 the legs fixed to the respective portions. To extend or contract the table I provide a suitable screw device operable by a crank from one end of the table. 5 indicates the screw arranged longitudinally of the table beneath the top and parallel therewith. The screw, 5 is fixed to a stud or bracket, 6 depending from the portion, 1 of the table top and telescopes within a sleeve or tube, 7 rotatably connected to the portion, 2. The sleeve, 7 is provided with a threaded portion, 8 to engage the threads of the screw, 5, and is supported in bearings in the depending brackets 9 and 10. The sleeve is rotatably mounted but longitudi- 95 100

nally fixed in the brackets, 9 and 10, and to this end the sleeve is shouldered as at 11 and 12, the shoulders bearing against the respective brackets, 9 and 10. The end of the 5 sleeve is squared as at 13 to receive the crank, 14 and it is obvious that by turning the sleeve by means of the crank the portions 1 and 2 of the table will be moved toward or from each other. It is evident that a screw 10 of any desired pitch may be employed but I prefer to employ a screw having a triple or quadruple thread in order to open and close the table more quickly.

Pivotaly mounted beneath the table and 15 to one of the portions, 1 or 2 are a pair of levers 15—15. It will be obvious that the levers may be attached or fixed to either of the portions, 1 or 2 but I have illustrated them upon the latter. The levers 20 are attached to the bracket, 10 the same affording an efficient means of attachment. Pivotaly connected to the free ends of the levers, 15 is one of the leaves, 16, 16' and 16" indicating the remaining leaves which are 25 superimposed upon the leaf, 16 when the table is closed or in contracted position. The leaf 16 is provided with the ears or lugs, 17 which are pivotaly connected to the levers 15 as at 18. Suitable means are provided to actuate the arms or levers 15 intermittently as the table is extended to raise the leaves successively into position, and to lock the leaves against further movement after having been placed in position. To this 35 end I provide the arms or levers 15 with a cam shaped lower edge and provide suitable means fixed to the portion, 1 of the table for coöperation therewith to actuate the levers. The cam shaped edge comprises the 40 straight portions, 15^a, 15^b, 15^c, and 15^d connected by the intermediate portions, 15^e.

Fixed to the portion, 1 of the table are a 45 pair of rods or arms, 20,—20 which extend beneath the portion, 2 of the table and are provided at their ends with rollers, 21 which engage the cam edge of the levers, 15. The arms or rods, 20 are preferably connected to the bracket, 6 and slide through guides or ways, 22 formed upon the bracket, 9 which 50 maintain the rollers 21 in position. When the table begins to open the roller, 21 travels along the portion, 15^a of the arm which at that time is parallel with the table top. As soon as the gap between the portions, 1 and 2 is of sufficient width to receive the leaf, 16", the roller, 21 engages the first portion, 15^e raising the levers sufficiently to lift the leaf into position. The portion, 15^b is then horizontal or parallel with the table top and the 60 roller travels along said portion until the table is opened sufficiently to receive the leaf, 16', after which the roller, 21 engages the next portion, 15^e raising said leaf into position and so on until all of the leaves are in

position. The weight of the leaves holds the 65 levers in engagement with the rollers, 21, hence, as the table is closed as soon as the roller passes from one straight portion of the cam edge to the other the leaves drop sufficiently to slide beneath the next succeeding 70 leaf and so on until the table is in closed position as shown in Fig. 5. It should be noted at this point that the portions, 1 and 2 of the table are so proportioned that when the leaves are arranged beneath the inner end 75 of the portion, 1 they will lie in the center of the table; in other words the length of the portion, 1 is equal to the length of the portion, 2 plus the width of one of the leaves. It will be noted that, in opening the table, 80 after each leaf is raised in position the remaining leaves are drawn from beneath it, hence means must be provided for locking each leaf against further movement after it is raised into position. To this end I provide 85 each leaf with means for automatically locking it to the portion, 1 of the table or to the preceding leaf. This may be accomplished in various ways, but I find that shown in the drawings simple and efficient. 90 Secured to the bottom of each leaf are a pair of metal plates, 23 which project beyond the edge of the leaf in the direction of the portion, 1 of the table and equipped with pins, 24 which extend upwardly to engage holes, 95 25 formed in the lower face of the portion, 1 of the table and the several leaves. As each leaf is raised into position, the pins, 24 engage the holes, 25 in the portion, 1 or in the preceding leaf and prevent further movement of 100 the leaf longitudinally of the table.

As the lower leaf is the only one which is attached to the levers, 15 and as the others merely rest thereon means must be provided for maintaining the superimposed leaves in 105 position and for moving them forwardly into position to be raised, or backwardly under the table. To this end the leaves are arranged between vertically disposed guides fixed to the portion, 2 of the table. These 110 comprise a pair of members, 26, depending from the portion, 2 of the table and having their edges extending beyond said portion to form ways for the leaves, the leaves being provided with notches, 27 to receive them, 115 and the members, 28 arranged upon the opposite sides of the leaves. The members, 26 and 28 are fixed to the portion, 2 of the table and move therewith and the leaves are vertically movable between them. The members, 28 are fixed to telescoping devices secured to the portions, 1 and 2 of the table. These devices are preferably arranged between the legs of the table but may be fixed thereto in any other suitable manner. 120 Secured to the legs, 4 are the tubular members, 29 into which telescope the members, 30 secured to the legs, 3. The members, 28

- are fixed to the ends of the members, 29 and extend upwardly into longitudinal grooves, 31 formed in the under face of the portion, 1 of the table, the upper ends of the members 5 being flanged as at 32 to rest against the top of the groove, 31. As the table is opened the members, 28 push the leaves, 16'—16" forwardly maintaining them in position above the leaf, 16. As each leaf is raised 10 into position by the cam levers, 15 the members, 28 pass beneath them and support them in position after the remaining leaves are drawn from beneath them, the leaves being grooved as at 31' to receive the upper 15 edge of said members. The edges of the plates, 23 are arranged to overhang the grooves, 31' to such an extent as to extend beneath the flange, 32. This prevents the leaves being raised above the level of the table top. To prevent the last or bottom leaf, 16 from raising above the table top it is provided with the lugs, 33 preferably formed as 20 extensions of the strips, or plates, 23 and which engage the bottom face of the portion, 25 2 of the table top. The table is preferably provided with a depending finishing molding, 34, the bottom edge of which is flush with the bottom of the leaf, 16 when the table is in closed position as shown in Fig. 5, the whole 30 presenting a neat appearance and the molding serving to screen the greater part of the mechanism from view.
- Having described my invention what I claim as new and desire to secure by Letters 35 Patent is:
1. An extension table comprising the two end portions adapted to be moved toward or from each other, in combination with a plurality of leaves arranged one above the other 40 beneath the table top when in closed position, a lever pivotally connected to one portion of the table and having its free end arranged beneath said leaves and means for intermittently raising said lever as the end portions of the table are moved apart to raise the leaves successively into position flush with the top of the table, substantially as described.
  2. An extension table comprising the two 50 end portions adapted to be moved toward or from each other, in combination with a pair of levers pivotally mounted beneath one of said end portions, a plurality of leaves arranged one above the other when the table is in closed position and supported upon the free ends of said levers and means for intermittently raising said levers as the table is extended to raise the leaves successively into position flush with the table top, substantially as described.
  3. An extension table comprising the two 60 end portions adapted to be moved toward or from each other, in combination with a plurality of leaves arranged one above the other
- beneath the table top when in closed position a lever pivotally connected to one portion of the table and having its free end arranged beneath said leaves and means upon the opposite end portion for intermittently raising said lever as the table is extended to 65 raise the leaves successively into position flush with the table top, substantially as described.
4. An extension table comprising the two end portions adapted to be moved toward or 70 from each other, in combination with a plurality of leaves arranged one above the other beneath the table top when in closed position, a lever pivotally connected to one portion of the table and having its free end arranged beneath said leaves, said lever having a cam shaped lower edge, and means fixed to the other portion of the table for engaging said cam shaped edge to raise said leaves successively into position flush with the 75 table top, substantially as described.
  5. An extension table comprising the two end portions adapted to be moved toward or 80 from each other, in combination with a plurality of leaves arranged one above the other beneath the table top when in closed position, a pair of levers having cam shaped lower edges pivotally connected to one of said end portions and having their free ends arranged beneath and supporting said leaves 85 and means fixed to the other end portion and extending beneath said levers into engagement with the cam shaped portion thereof and supporting said levers and said leaves, substantially as described.
  6. An extension table comprising the two end portions adapted to be moved toward or 90 from each other, in combination with a plurality of leaves arranged one above the other beneath the table top when in closed position, a pair of levers having cam shaped lower edges pivotally connected to one of said end portions and having their free ends arranged beneath and supporting said leaves 95 and means fixed to the other end portion and extending beneath said levers into engagement with the cam shaped portion thereof and supporting said levers and said leaves, substantially as described.
  7. An extension table comprising the two 100 end portions adapted to be moved toward or from each other, in combination with a plurality of leaves arranged one above the other beneath the table top when in closed position, a lever pivotally connected to one portion of the table and having its free end arranged beneath said leaves, means carried by the same portion of the table for maintaining said leaves in fixed longitudinal relation therewith while being raised or lowered, means for intermittently raising said lever as the end portions of the table are moved apart to raise said leaves successively into position flush with the top of the table, and 105 means upon the edges of the leaves for locking the successive leaves against longitudinal movement after they are raised into position, substantially as described.
  8. An extension table comprising the two 110 end portions adapted to be moved toward or from each other, in combination with a plurality of leaves arranged one above the other and beneath one of said end portions, a lever pivotally mounted beneath the other end portion and extending beneath said leaves, means for intermittently raising said lever as the end portions of the table are moved 115

apart to raise the leaves successively into position flush with the table top and suitable guides for maintaining said leaves in position one above the other when beneath the level of the table top, substantially as described.

In testimony whereof I have signed my

name to this specification in the presence of two subscribing witnesses.

CHARLES H. JOHNSEN.
